DRAFT CONTROL MECHANISM

Ross B. Cranmer, Barnegat, N. J.

Application July 25, 1938, Serial No. 221,246

1 Claim. (Cl. 126—289)

This invention relates to draft control mechanism the primary object of the invention being to provide means for controlling the combustion and regulating the draft within the fire box of a furnace, cooking or heating stove, by raising and lowering the pressure under the grate, without the necessity of opening the doors or other closures above the fire, which usually liberates, injurious gas and smoke fumes, to the atmosphere of the room.

An important object of the invention is to provide a device of this character which will permit of an adjustment with such a degree of fineness, that absolute control of the burning of the fuel will be insured.

A still further object of the invention is the provision of a draft control which will confine the heat and prevent the exhausting of the heat through the chimney, when the draft to the furnace or stove is checked.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawing:

Figure 1 is a fragmental sectional view through a stove equipped with a draft control constructed in accordance with the invention.

Figure 2 is a sectional view taken on line 2—2 of Figure 1.

Figure 3 is an elevational view of the control handle.

Figure 4 is a sectional view taken on line 4—4 of Figure 3.

Referring to the drawing in detail, the reference character 5 designates the body portion of a stove structure, however, it is to be understood that the principle of the invention may be carried out in a furnace, with equally as effective results.

The reference character 6 designates the fire box of the stove which includes grate bars 7 under which the usual ash pit 8 is located. Openings 9, at the rear end of the ash pit establish communication between the ash pit 8 and vertical flue 10 that in turn communicates with the chimney of the stove, to the end that a draft of air may circulate through the ash pit, under the fire in the fire box, escaping through said flue

and eliminating any possibility of the air passing upwardly through the fire box.

Bearings 11 are secured to the body portion and accommodate the damper rod 12, which is of a length to extend through an opening formed in one side of the stove, where it is supplied with a handle 13 that is secured to the rod 12, by means of the screw 14 which is threaded in the tube 15. The tube 15 is provided with a shoulder 16 that engages the block 17, forcing the block 10 into engagement with the stop 18, securing the handle 13 and damper rod, against movement after it has been properly set. Graduations are provided on the stop 18, to insure the accurate setting of the handle.

As clearly shown by Figure 2, the damper rod 12 is provided with an offset portion 19 adapted to fit over the lug 20 extending from the damper 21, the damper 21 being of a length to close both of the openings 9. A cotter key indicated by the reference character 22 is extended through an opening in the lug 20 and engages the rod 19, securing the damper to the rod 12 so that movement of the rod 12, will act to open or close the damper 21. Secured to the damper 21, are hinges 23 which have openings to receive the rod 12, as clearly shown by Figure 2 of the drawing.

From the foregoing it will be seen that due to the construction shown and described, the damper 21 may be moved to a position to allow air to pass through the ash pit 8, exhausting through the flue 10, thereby insuring against air passing upwardly through the fire box to cause the fire to burn.

It might be further stated that the device may be used to control the draft through the fire box, eliminating the necessity of opening the top of the stove allowing air to pass over the fire, which usually results in wasted heat and too rapid cooling of the stove.

I claim:

A stove damper comprising a pair of spaced bearing members, a damper section, bearings on said damper section and held between the first mentioned bearing members, a lug formed centrally of the damper section, an operating rod extending through said bearings, an offset portion formed on the rod and fitted around the lug, a key extending through the lug and engaging the offset portion of the rod securing the damper section to said rod, and means for securing the rod in various positions of adjustment.
